CLAIM

I claim the ornamental design for a light fixture, as shown and described.

DESCRIPTION

FIG. 1 is a front view of a first embodiment of my design for a light fixture;

FIG. 2 is a right side view of the light fixture embodiment shown in FIG. 1;

FIG. 3 is a left side view of the light fixture embodiment shown in FIG. 1;

FIG. 4 is a top plan view of the light fixture embodiment shown in FIG. 1;

FIG. 5 is a bottom view of the light fixture embodiment shown in FIG. 1;

FIG. 6 is a rear view of the light fixture embodiment shown in FIG. 1;

FIG. 7 is a front view of a second embodiment of my design for a light fixture;

FIG. 8 is a right side view of the light fixture embodiment shown in FIG. 7;

FIG. 9 is a left side view of the light fixture embodiment shown in FIG. 7;

FIG. 10 is a top plan view of the light fixture embodiment shown in FIG. 7;

FIG. 11 is a bottom view of the light fixture embodiment shown in FIG. 7; and,

FIG. 12 is a rear view of the light fixture embodiment shown in FIG. 7.

The broken lines shown in the various figures are for illustrative purposes only and form no part of the claimed designs.
